UNITED STATES PATENT OFFICE.

ALFRED E. KNIGHT, OF SOMERVILLE, MASSACHUSETTS, ASSIGNOR TO
JAMES H. CHURCHILL, TRUSTEE, OF QUINCY, MASSACHUSETTS.

STORAGE BATTERY.

No. 798,906

Specification of Letters Patent.

Patented Sept. 5, 1905.

Application filed November 16, 1904. Serial No. 232,973.

To all whom it may concern:

Be it known that I, ALFRED E. KNIGHT, a citizen of the United States, residing in Somerville, in the county of Middlesex and State 5 of Massachusetts, have invented an Improvement in Storage Batteries, of which the following description, in connection with the accompanying drawings, is a specification, like characters on the drawings representing like parts.

This invention relates to storage batteries, and has for its object to increase the life and efficiency of the same.

In storage batteries the chemical combinations which take place increase in volume the oxids of lead formed on the positive plate or electrode, with the result that the said plate in time is caused by this increase or "growth," as it is frequently called, to warp or buckle 20 and sometimes to crack. In the case of a buckled plate it frequently occurs to such extent as to effect contact between the positive and negative plates of the battery, thereby producing a short circuit and causing very 25 rapid deterioration of the plates and impaired service.

The present invention has for its object to overcome or at least reduce to a minimum the buckling or warping of the plates, which is 30 due to expansion of the same, and for this purpose provision is made for restricting the buckling or distortion of the plates under the influence of expansion, so that soft-metal plates, such as lead plates, as well as composition plates, may be used for storage batteries 35 without danger of short circuiting, thereby increasing the life and efficiency of the battery.

The buckling or warping of the battery- 40 plates may be prevented by means which guide the plate in its expansive movement and cause the same to move in a straight or substantially straight path, or the buckling may be minimized or localized, as will be described. 45 I prefer to use both features in conjunction, or either alone may be used, as will be described.

Figure 1 is a vertical section of a storage battery provided with plates embodying this 50 invention; Figs. 2, 3, and 4, details to be referred to; Fig. 5, a modified form of plate to be referred to; Figs. 6 and 7, details in plan and perspective to be referred to; Fig. 8, a front elevation of another modified form of

plate to be referred to; Fig. 9, an end elevation of the positive and negative plates employed in the cell shown in Fig. 1; and Figs. 10 to 33, inclusive, modifications to be referred to; Fig. 34, a detail in side elevation of the supporting-plate shown in Fig. 1, and Fig. 35 a plan view of a modified form of guide to be referred to.

Referring to Fig. 1, *a* represents one form of storage-battery cell such as now commonly used in electric-light plants, it comprising a 65 wooden box or cell provided with a lead lining *b* and glass plates *c*, upon which rest the plates *d e* of the storage battery by means of lugs *f*, the said plates being provided on one side with longer arms or lugs *g*, to which 70 the usual bus-bars or conductors (not shown) are connected. The plates *d e* are arranged in pairs, the plate *d* being the positive plate and the plate *e* being the negative plate, and said plates in practice are arranged substantially close together and are separated by glass rods *i*, which are arranged at suitable distances apart. The present invention has for its object to prevent or reduce to a minimum buckling or warping of the plates, and 75 especially the positive plates *d*, and this result may be accomplished by providing a guide for the plate in its expansive movement, whereby the plate in its expansive movement may be guided or directed in a 80 substantially straight path, or the buckling of the plate may be localized by one or more slots or cuts formed in the plate and extended to one side or edge thereof, and while I prefer to employ both methods in conjunction I 85 do not desire to limit my invention in this respect, as good results may be obtained with either alone. In the present instance I have shown the positive plate *d* as provided with a plurality of slots *k*, which extend from one 90 side or edge toward but not to the opposite side or edge of the plate, so that the latter is composed of an unslotted portion *m*, from which extend a plurality of arms *n*, separated from each other by slots or spaces *k*, which 95 may be of any desired width and sufficient to allow for the expansion of the metal laterally with relation to said slot without making contact with adjacent arms. In the present instance the slots *k* are shown as extending from 100 the lower edge or side of the plate toward the upper end thereof, and said slots may be made straight, as represented in Figs. 1, 2, 105

and 9, or they may be curved, as represented in Fig. 5, or they may be of other forms. The arms or strips *n* formed by the slots may have coöperating with them a guide *o*, 5 extended transversely of the arms and so constructed as to allow the arms to expand laterally, yet such as to guide the said arms in their expansive movement and cause them to expand in a straight or substantially 10 straight path. In Figs. 1 and 2 the guide *o* is shown as composed of side bars connected by end bars *q* and by intermediate bars *r*, which form openings *s*, through which are extended narrower end portions or fingers *w* of the 15 arms *n*, the guide being secured to the plate by pins 40 of lead or other suitable material extended through the fingers *w* and upon which the side bars of the guide rest. (See Figs. 2 and 9.) The pins 40 are shown separately in Fig. 3. The openings *s* are made 20 longer than the width of the fingers *w*, so as to permit the latter to expand freely in a lateral direction. The plate *d* may also be guided, if so desired, by means of lugs or projections 25 37 on the plates, which extend through slots 38 in the supporting-plates *c*. The slots 38 may be made separate from each other, as represented in Figs. 1 and 34, or they may be connected to form one continuous slot. 30 In Fig. 4 the guide *o* is shown as open at its ends, the end bars *q* (shown in Fig. 2) being omitted.

In Figs. 5, 6, and 7 the guide *o* is shown as a bar provided with a groove 43, having openings *s* at its opposite ends through which the fingers *w* on the outside arms *n* may extend, the intermediate arms of the plate extending 35 into the groove 43, but not through the same. The guide *o* shown in Figs. 5, 6, and 7 may have notches 45 formed in its opposite sides 40 for the passage of the spacing rods or bars *i*. In Fig. 1 the spacing rods or bars *i* terminate above the guide. In Fig. 5 the guide is secured to the plate by pins 40, which extend 45 through the fingers *w*.

Figs. 10 to 33 and Fig. 35 show various modifications of guides and the manner of securing them to the plates. In Figs. 10 and 11 the guide *o* is shown as a bar provided with a 50 groove 43 and the pins 40 extend through the side walls of the groove and the plate *d*. In Figs. 12 and 13 the guide *o* is shown as two side bars pinned to the plate. In Figs. 14 and 15 the guide *o* shown in Fig. 5 is represented 55 in end view and plan. In Figs. 16 and 17 the guide *o* is shown without end walls and the pins 40 extend through the guide and plate. In Fig. 18 the guide *o* shown in Fig. 8 is represented in end elevation, the guide being 60 shown as a grooved bar which is provided with a groove 60 on its under side to fit over the uprights or supports 61. In Fig. 19 the guide *o* shown in Fig. 20 is provided with a single slot through which the plate extends and the 65 pins 40 are extended through slots 62 in the

sides of the guide-bar. In Fig. 21 the guide *o* is shown as a flat bar which is inserted between the forked lower end of the plate and rests on the pins 40, which extend through the forks of said plate. In Fig. 23 the guide *o* is 70 shown as a triangular-shaped bar about which the end of the plate is folded. In Fig. 25 the guide *o* is shown as a round rod or bar about which the end of the plate is folded. In Fig. 27 the guide *o* is shown as two rods about 75 which the lower edge of the plate is folded, the latter being split for this purpose to form fingers 65, and alternate fingers are folded around the rods. In Figs. 29 and 30 the guides are shown as two flat bars which fit into recesses or channels 67 in the plate and are pinned thereto. In Figs. 31 and 32 the guide is shown as a grooved bar having holes in the bottom wall of the groove through which fingers 68 are inserted and bent to secure the guide to 80 the plate. In Fig. 33 is shown a side elevation of the construction represented in end elevation in Fig. 25. In Fig. 35 the guide *o* is shown as a sheet provided with slots 70, through which the lower ends of the plate *d* 85 may extend.

From the above description and illustrations it will be seen that the tendency of the positive plate to buckle is resisted by the guide *o*, which causes the said plate as it expands to 90 move in a straight or substantially straight path, thereby avoiding the injurious effects above noted. I may prefer to employ the guide with a positive plate which is slotted to form arms; but I do not desire to limit my 100 invention in this respect, as the guide may be used to advantage with a plate which is not slotted or the slotted plate may be used without the guide. In this latter case the buckling of the arms *n* may not be entirely prevented, 105 but it will be localized and confined to the individual arms, with the result that the slotted plate will not be buckled to any material extent even after long use.

The invention herein described is adapted 110 to be used with the harder or composition plates now commonly employed in storage batteries; but it is especially efficient, inasmuch as it enables the plates of the battery to be made of soft metals—such, for instance, as 115 soft lead—without danger of the soft-metal plates buckling to such extent as to injure the plate or impair the efficiency of the battery and at the same time materially increasing the life of the battery and reducing the 120 cost of maintenance of the same.

In Fig. 1 it will be seen that the plate at its upper end rests on the supports *c* and is practically anchored at that end, while the lower end of said plate is unsupported and is free 125 to expand.

I prefer to have the slots *k* extend to the side or edge of the plate and to have the arms disconnected at the side or edge of the plate; but I wish it to be understood that if the arms 130

should be connected at the side or edge of the plate by a film or strip of metal so thin as to be readily broken by the expansive action such construction I deem within the scope of my invention. In practice the positive plate is extended below the negative plate to avoid a short circuit by contact of the guide with the negative plate and also to afford ample clearance for any sediment which might drop between the two plates and be liable to lodge on the said guide.

I claim—

1. In a storage battery, in combination, a battery-plate provided with slots extended from one edge or side to form arms having their edges separated from one another, a guide loosely applied to the plate and extended transversely of said arms to direct said arms in their expansive movement laterally, and means to secure said guide to said plate.

2. In a storage battery, in combination, a positive plate, a guide loosely applied to said plate and coöperating with one edge of the said plate to permit expansion of the same and yet resist buckling of said plate, and means to secure said guide to said plate.

3. In a storage battery, in combination, a battery-plate suspended at its upper end and having its lower end free, and means loosely applied to said plate transversely thereof to permit free lateral movement of said plate and to guide the same in its lateral movement, for the purpose specified.

4. In a storage battery, in combination, a plate suspended at its upper end and having its lower end free, and means loosely applied to the lower free end of said plate to permit lateral expansion yet resist buckling of said plate.

5. In a storage battery, in combination, a positive plate and a negative plate, one of the said plates being extended below the other, and a guide coöperating with a portion of the plate extended below the other to permit expansion and yet resist buckling of the plate which is extended below the other, said guide being loosely applied to the plate with which it coöperates, substantially as described.

6. In a storage battery, in combination, a

battery-plate, supports for the opposite sides of said plate provided with slots, and means attached to said plate intermediate its ends and extended loosely into said slots to move therein and guide the plate in its expansive movement, substantially as described.

7. In a storage battery, in combination, a battery-plate provided with a projection intermediate its ends, and means having a slot into which said projection is loosely extended to permit movement of said projection in said slot for guiding said plate in its expansive movement, substantially as described.

8. In a storage battery, in combination, a battery-plate substantially anchored at one end and having its opposite end free to expand in one direction, and means loosely applied to said plate and coöperating with the free end thereof to permit expansion of the plate in a direction substantially at right angles to the first-mentioned direction and yet resist the buckling or distortion of the plate by the expansion in the second-mentioned direction.

9. In a storage battery, in combination, a plate, a support for one side of said plate provided with a slot, means attached to the said plate intermediate its ends and extended loosely into said slot to move therein, and a guide loosely applied to one edge of said plate to permit expansion of the same and yet resist buckling of the said plate, substantially as described.

10. In a storage battery, in combination, a battery-plate in a substantially non-oxidized condition substantially anchored at one end and having its opposite end free, and means loosely applied to the free end of said plate to permit free lateral movement of said plate as it is oxidized and yet resist buckling of said plate under the influence of such oxidation, substantially as described.

In testimony whereof I have signed my name to this specification in the presence of two subscribing witnesses.

ALFRED E. KNIGHT.
